CLAIM

The ornamental design for a shirt, as shown and described.

DESCRIPTION

FIG. 1 is a front perspective view of a shirt, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is an enlarged perspective view thereof, taken from encircled portion 8 in FIG. 1.

The broken lines in the drawings illustrate the portions of the shirt, which form no part of the claimed design.

The pattern applied to the surface of the shirt is surface ornamentation.

1 Claim, 8 Drawing Sheets
